UNITED STATES PATENT OFFICE.

ALFRED FORNANDER, OF NEW YORK, N. Y., ASSIGNOR OF ONE-HALF TO JOSEPH W. HEIMSOOTH, OF NEW YORK, N. Y.

Mounting for Electric Lamps.

1,168,620.

Specification of Letters Patent. Patented Jan. 18, 1916.

Application filed April 2, 1914. Serial No. 829,046.

To all whom it may concern:

Be it known that I, ALFRED FORNANDER, a subject of the King of Sweden, and resident of New York city, in the county and State of New York, have invented certain new and useful Improvements in Mountings for Electric Lamps, of which the following is a specification.

My invention relates to mountings for electric lamps, and more particularly for incandescent lamps, the more particular purpose of my improvement being to promote the simplicity of construction, the use of standard material and even scrap material as far as practicable, and to give the lamp mounting a large variety of distinct functions, so as to increase the adaptability and general efficiency of the lamp.

Reference is made to the accompanying drawings forming a part of this specification, and in which like letters indicate like parts.

Figure 1 is a side elevation of the mounting complete. Fig. 2 is a plan view of the spool and parts associated therewith, serving as a base. Fig. 3 is a detail view, showing the construction of the eye used for guiding the lamp cord, and as a pivotal support for the lamp socket. Fig. 4 is a cross section through the base. Fig. 5 is a side elevation, showing the mounting as supported upon a wall by aid of a suction cap, forming a part of the device. Fig. 6 is a fragmentary side elevation, showing the lamp and parts associated therewith as supported upon a board by spring pressure. Fig. 7 is a detail view, showing in cross section the suction cap. Fig. 8 is a detail view, showing improved means for enabling the lamp socket to be turned.

A pair of metallic spool members 9, 10, made substantially alike, are provided, each of these parts being preferably stamped from a single sheet of metal, which may or may not be scrap material. These spool members are provided, respectively, with cup-like bottoms 11, 12, and are so proportioned that when these bottoms are placed together, as indicated in Fig. 4, the outer peripheral edges of the spool members will be spaced apart, thus forming a groove 13 which merges into an annular passage 14, the cross diameter of which is much greater

than the width of the groove 13. The spool member 9 is provided with a hole 15. A 55 clamping disk 16 is provided with a hook 17 which fits into the hole 15. A clamping bolt 18 extends through the clamping disk 16, and also through the bottoms 11, 12 of the spool members. 60

A supporting stem 19, made of a single piece of spring wire, is provided with a portion 20 bent substantially into annular form, this portion being disposed between the clamping disk 16 and the bottom 11. The 65 bolt 18, by exerting pressure upon the clamping disk 16, causes this disk to press upon the annular portion 20 of the supporting stem. The clamping disk 16 is provided with a notch 16^a through which the stem 19 70 extends, as may be understood from Fig. 2. The spring stem 19 is bent to form a convolution 21, and is provided with a backwardly extending portion 22, the latter being provided with a convolution 23. The 75 portion 22 of the spring stem is further provided with a part 24 integral with it, this part supporting a suction cap 26, which is provided with a thick portion 25 through which the part 24 extends, and into which 80 it fits tightly.

A friction ring 26^a is engaged externally by the convolution 21. A piece of spring wire 28 is provided with a convolution 27 engaging the friction ring 26^a externally. 85 The piece of spring wire 28 is further provided with a portion 29 integral with it and bent into annular form, so as to constitute a convolution. This convolution fits into a groove 30 carried by a lamp socket 31, so as 90 to support this lamp socket, as indicated in Fig. 1. A lamp cord 32 extends into the lamp socket 31, in the usual or any desired manner. Connected with this lamp cord is a cord socket 33 which may be fitted into an 95 electrolier or other appropriate part from which the electric current is to be supplied. The lamp cord 32 carries a bead 34, which, in this instance, is made of soft rubber. The bead can be crowded through the groove 13, 100 as indicated in Fig. 1, and thus serves as a fastening for preventing the lamp cord from becoming unwound.

A wall is shown at 35, and my device may be supported directly from the wall 105 even if the latter be smooth, by aid of the

suction cap 26. If desired, the device may be mounted upon a board 36, which may be a piece of furniture, such as the back of a chair, the parts being arranged as indicated in Fig. 6. The socket 31 carries a thumb-piece 37 for turning the current on and off. An incandescent bulb 38 is detachably connected with the socket 31, in the usual or any desired manner.

10 The operation of my device is as follows: The parts being assembled and arranged as indicated, the various movable parts may be shifted in position for different purposes. If the device is to be stored away or carried 15 in the pocket, the lamp cord 32 is wound around upon the spool member, as indicated in Fig. 1, the bead 34 being pressed through the groove 13, and thus preventing the cord from becoming unwound. The bulb 38 may 20 be removed from the socket 31, and this socket bent down, upon the friction ring 26^a as a center, and thus brought into the position indicated by dotted lines in Fig. 1. The portion 22 of the spring stem is 25 sprung into the position indicated in Fig. 1, the suction cap 26 being turned, if desired, upon the part 24 as a center, and thus rested upon the bolt 18 or upon the clamping disk 16. The device now occupies a 30 comparatively small space. In order to mount the device upon the wall 35, the portion 22 of the spring stem is sprung outwardly so as to clear the spool member 9, or in other words, is brought into its normal 35 position. The suction cap 26 is next pressed against the wall 35, so that the spool is located directly below the suction cap. The socket 31 may now be bent upwardly or downwardly to any desired angle.

40 If it be desired to turn the socket 31 in a horizontal plane, the suction cap is detached from the wall and moved substantially to the same horizontal level as the axis of the spool, and then screwed to the wall by suction. The socket 31 may be turned relatively to the convolution 29, which serves as a bearing for supporting the same. The friction ring 26^a, besides serving as a bearing for the convolution 27, answers likewise 50 as an eye for guiding the lamp cord 32. When the device is to be mounted upon a board 36, as indicated in Fig. 6, the spool is placed upon one side of the board, and the portion 22 of the spring stem is sprung over 55 to a point adjacent the opposite side thereof, so that the portion 25 of the suction cap presses against the board 36, at a point opposite the location of the spool. The device is thus held by spring pressure upon the 60 board, and may be adjusted as above described. As the hook 17 prevents rotation of the clamping disk 16, the spring stem 19 maintains always the same position relatively to the spool when the parts are assembled 65 as indicated in Fig. 4.

I do not limit myself to the precise construction shown, as variations may be made therein without departing from the spirit of my invention, the scope of which is commensurate with my claims.

Having thus described my invention, what I claim as new and desire to secure by Letters Patent is as follows:

1. A mounting for electric lamps comprising a member serving as a base, a spring stem connected with said member and extending therefrom, said spring stem being provided with a convolution, a friction ring engaging said convolution, a lamp socket supporting member made of wire and provided with a convolution engaging said friction ring, and a lamp socket carried by said last mentioned member and movable into different angular positions relatively to said friction ring.

2. A device of the character described comprising a base member, a stem connected with said base member and extending therefrom, a friction ring engaging said stem, a lamp socket, a member connected with said lamp socket, and provided with a portion partially encircling said friction ring, and formed so as to exert pressure thereupon in order to hold said lamp socket in various angular positions relatively to said stem, and a lamp cord extending through said friction ring and guided thereby, said lamp cord being connected with said lamp socket and with said base.

3. A device of the character described comprising a pair of spool members provided with flat bottoms, a stem provided with an annular portion for engaging one of said bottoms, means for supporting a lamp upon said stem, a clamping disk engaging said annular portion of said stem, and a bolt extending through said clamping disk and through said bottoms.

4. A device of the character described comprising, a pair of spool members fitted together, one of said spool members being provided with a hole, a clamping disk provided with a hook for extending into said hole in order to prevent said clamping disk from turning relatively to said spool members, a stem provided with a portion located between said clamping disk and one of said spool members, and means for mounting a lamp upon said stem.

5. In a mounting for electric lamps, the combination of a spool adapted for use as a base, a spring stem mounted upon said spool and extending therefrom, said spring member being provided with a portion which may be sprung into different positions relatively to said spool, and a suction cap mounted upon said portion of said spring stem.

6. In a mounting for electric lamps, the combination of a spool, a spring stem ex-

tending from said spool and provided with a portion extending backwardly toward said spool, a suction cap carried by said portion and provided with a thickened part for making frictional engagement with a board or the like, said spring stem being of such form that by its distortion said spool and said suction cap can be located upon opposite sides of a board or the like so as to support 10 said stem, a lamp socket, and means for

pivottally supporting said lamp socket upon said spring stem.

In testimony whereof I have signed my name to this specification in the presence of two subscribing witnesses.

ALFRED FORNANDER.
